[57] CLAIM

The ornamental design for tire or similar article, as
shown and described.

DESCRIPTION

FIG. 1 is a perspective view of a tire or similar article
showing my new design, it being understood that the
tread pattern is repeated uniformly throughout the cir-
cumference of the tire;

FIG. 2 is a developed plan view of the tread surface
thereof on a reduced scale shown split in two sections
for convenience of illustration; and

FIG. 3 is a side elevation view thereof on a reduced
scale, the opposite side being a mirror image of that
shown.
